UNITED STATES PATENT OFFICE.

SIVERT MOE, OF CHICAGO, ILLINOIS, ASSIGNOR TO THE MIEHLE PRINTING PRESS & MANUFACTURING COMPANY, OF CHICAGO, ILLINOIS, A CORPORATION OF ILLINOIS.

BED-CUSHIONING DEVICE FOR PRINTING-PRESSES.

1,104,819.

Specification of Letters Patent.

Patented July 28, 1914.

Application filed July 3, 1912. Serial No. 707,408.

To all whom it may concern:

Be it known that I, SIVERT Moe, a citizen of the United States, residing at Chicago, in the county of Cook and State of Illinois, have invented certain new and useful Improvements in Bed-Cushioning Devices for Printing-Presses, of which the following is a specification.

This invention relates to an improved bed cushioning device for printing presses and is particularly applicable to cylinder presses having a curved bed and in which the bed movement is along a curved or arcuate path. In such presses dash pot cushioning devices have not been satisfactorily employed for the reason that the piston, moving in the curvilinear path of the bed by which it is carried, does not properly coact with the cylinder having a rectilinear bore.

The primary object of my invention is therefore the combination with a bed plate moving in a curved path, of dash pot cushioning mechanism in which the traveling element, whether piston or cylinder, moves in a rectilinear path, and I attain this object by so mounting the piston, for instance, upon the bed as to provide for rocking and vertical movement relative to the bed and by guiding the piston for movement with the bed but in a straight line coinciding with the axis of the stationary cylinder. Obviously the conditions may be reversed, the cylinder being mounted for movement in alinement with the axis of a stationary piston, the principle being the same although it is usually advantageous from a mechanical standpoint to mount the piston upon the bed or movable member and the cylinder upon the rigid frame or other support.

In order that the invention may be readily understood and the manner of its operation made evident I have in the accompanying drawings shown by way of illustration a preferred embodiment of the same.

In these drawings, Figure 1, is a partial side elevation of a printing press containing my invention with certain parts broken away and others shown in sections; Fig. 2, is a vertical section on the line 2—2 of Fig. 1; Fig. 3 is a horizontal transverse section on the line 3—3 of Fig. 2; Fig. 4 is a vertical longitudinal section on the line 4—4 of

Fig. 2; Fig. 5 is a transverse vertical section on the line 5—5 of Fig. 3, and Fig. 6 is a perspective detail. 55

Having detailed reference to the drawings reference numeral 11 designates the frame of a printing press with which is assembled the impression cylinder 12, the bed 13, and the ordinary auxiliary parts which form no 60 part of the present invention and which are merely indicated for purposes of orientation. In lithographic presses of the type illustrated the surface of the bed 13 viewed longitudinally is curvilinear being formed 65 upon the arc of a circle having comparatively a very large radius, approximately 50 feet. This bed upon which the form is carried and which coacts with the cylinder 12 is given a longitudinal reciprocating movement by mechanism not shown, and moves 70 in a curvilinear path upon a carriage 14 traveling upon rolls 15 upon a suitable track 16 of the frame 11.

It is necessary that cushioning devices of 75 some sort be employed to absorb the momentum of the bed at the two extremes of its path where the direction of movement is reversed and it has been customary to so cushion the movement of printing beds moving in a rectilinear path by employing the well-known dash pot mechanism. Where the movement of the bed is along a curved path, however, as in printing presses of this type, it has not been found practicable to 80 employ a dash pot cushioning mechanism for the reason, as stated, that the path of the piston carried by the bed does not coincide with the bore of the cylinder, the path of the former being along a curved line and 85 the bore of the latter necessarily about a rectilinear axis. I have overcome this difficulty in the following manner.

Fixedly mounted upon the frame 11 of the press are shown the oppositely facing cylinders 17, 17 while the coöperating pistons 18, 18 are shown as having their piston rods 19, 19 rigidly seated at their inner ends 20, 20 within the cross head 21. This cross head has extending from the two sides thereof 100 arms 22, 22 which arms carry plates 23, 23 traveling in rectilinear guide grooves 24, 24 formed in the opposite sides of the frame 11 and extending longitudinally thereof. By

this guiding connection between the cross head 21 and the frame 11 the pistons 18 are at all times caused to travel in alinement with the axes of the cylinders 17 whereby 5 accurate registration of the piston and cylinder is secured.

In order to provide for a connection between the cross head and the bed so that there shall be no relative longitudinal movement 10 of the two and the cushioning action shall be transmitted from the dash pot through the cross head to the bed and yet to provide for such relative transverse and rocking movement as shall permit the cross head to 15 travel in a rectilinear path while the bed travels in a curvilinear path I provide a flexible connection between the cross head and bed as follows: The cross head 21 is provided with a vertical slot 25 which may 20 have vertical side walls 26 and is provided with concentrically curved end walls 27, 27. Within this slot is positioned a shoe 28 having its exterior end walls 29, 29 curved to conform to the inner walls 27 of the cross 25 head and having one side face cut away at 30 to provide a slot for the reception of the lower portion of the stem 31, the upper end of which is flanged outwardly at 32 and rigidly secured by the bolts 33 to the traveling 35 bed.

It will be readily understood that the stem 31 is capable of vertical movement within the shoe 28 while the shoe is capable of rocking pivotal movement within the cross 35 head. In the medial position of the parts indicated in Figs. 1 and 4 of the drawing the stem 31 is vertical and at right angles to the cross head and piston rods, whereas at the two extremes of its curved path the stem will 40 be inclined to the vertical and to the cross head, such inclination in the two directions being rendered possible by the rocking movement of the shoe within the cross head. In the medial position also the bed is disposed 45 at a greater distance above the cross head than at the two extremes of its path and consequently as the bed and cross head travel in either direction the stem will move downwardly within the shoe. At all times, however, 50 the cross head is firmly coupled to the bed so far as concerns longitudinal movement, the two parts traveling together as an entirety.

The arrangement of the coupling members 55 as shown enables the several parts to be quickly assembled and dis-assembled, it only being necessary to lift the stem with the bed out of the shoe or by removing the guide plates to drop the cross head with the piston 60 tons from the stem. The shoe itself is readily removed from its seat within the cross head by rotating the same in a vertical plane through an angle of 90 degrees when it may be taken out. The parts may be reassembled 65 by reversal of these operations, it being

noted that there are no fastening devices connecting these coupling parts together.

While I have shown and described with a considerable degree of particularity the constructional features of one form of the invention it will be obvious that many mechanical changes could be made without sacrificing the inherent advantages of the invention and without departing from the scope of the invention as set forth in the 75 claims.

I claim:

1. The combination, with a stationary member, and a reciprocatory member mounted thereon to travel in an arcuate path, of 80 dash pot cushioning mechanism, one of the dash pot elements rigidly mounted on the stationary member with its axis at a slight angle to the path of the reciprocating member, the other dash pot element attached to 85 and moving in the same general direction as the reciprocating member, and means to guide the movably mounted element in a path parallel to a chord of the arc traversed by the reciprocating member and in alinement with the fixed element, substantially as 90 described.

2. The combination, with a stationary member, and a reciprocatory member mounted thereon to travel in an arcuate path, of 95 dash pot cushioning mechanism comprising a cylinder element rigidly mounted upon the stationary member and a piston element attached to and moving in the same general direction as the reciprocating member, and means to guide the piston element in alinement with the axis of the cylinder element 100 in a path corresponding to a chord of the arc traversed by the reciprocating member and substantially as described.

3. The combination, with a stationary member, and a reciprocatory member mounted thereon to travel in a curvilinear path, of dashpot cushioning mechanism comprising a cylinder and piston elements, one of 110 said elements rigidly mounted on the stationary member and the other element carried by the reciprocating member, a connection between the last named element and the reciprocating element to permit of transverse relative movement, and means to guide the movable element in a rectilinear path in alinement with the axis of the stationary element, substantially as described.

4. The combination, with a stationary 120 member, and a reciprocatory member mounted thereon to travel in a curvilinear path, of dash pot cushioning mechanism comprising a cylinder element rigidly mounted on the stationary member and a piston element 125 carried by the reciprocating member, a connection between the piston element and the reciprocating member to permit of rocking and transverse relative movement, and means to guide the piston element in a rec- 130

tilinear path in alinement with the axis of the cylinder element, substantially as described.

5. In a printing press, the combination, with the frame and a reciprocatory bed traveling longitudinally thereof in a curvilinear path, of cushioning mechanism comprising dash pot elements carried one by the frame and the other by the bed, one of the dash 10 pot elements rigidly mounted, the other dash pot element mounted to provide for lateral and rocking movement, and means to guide the reciprocating element along a rectilinear path in alinement with the stationary element, substantially as described.

6. In a printing press, the combination, with a frame, and a reciprocatory bed traveling longitudinally thereon in a curvilinear path, of cushioning mechanism comprising 20 a dash pot, one of the dash pot elements rigidly mounted on the frame, the other dash pot element carried by the bed and mounted for lateral and rocking movement thereon, and means to guide the movable element in a 25 rectilinear path in alinement with the stationary element, substantially as described.

7. In a printing press, the combination, with a frame and reciprocatory bed traveling longitudinally thereof in a curvilinear path, of cushioning mechanism comprising 30 a dash pot, the cylinder rigidly mounted on the frame, the piston carried by the bed and mounted for lateral and rocking movement thereon, and means to guide the piston in 35 a rectilinear path in alinement with the cylinder, substantially as described.

8. In a printing press, the combination, with a frame, and reciprocatory bed traveling longitudinally thereon in a curvilinear 40 path of a dash pot cushioning mechanism comprising a pair of cylinders fixed in opposition to each other near the ends of the frame, a pair of pistons mounted for reciprocatory rectilinear movement between and 45 in alinement with the cylinders, and a connection between the pistons and reciprocatory bed, said connection providing for lateral and rocking movement of the bed relative to the pistons, substantially as de- 50 scribed.

9. In a printing press, the combination, with a frame, and reciprocatory bed traveling longitudinally thereon in a curvilinear

path, of a dash pot cushioning mechanism comprising a pair of cylinders fixed in opposition to each other near the ends of the frame, a pair of pistons mounted for reciprocatory rectilinear movement between and in alinement with the cylinders, a cross head connecting the pistons, said cross head having a transverse aperture, and a stem rigidly affixed to the bed and extending laterally therefrom into the aperture of the cross head, substantially as described. 55

10. In a printing press, the combination, with a frame, and reciprocatory bed traveling longitudinally thereon in a curvilinear path, of a dash pot cushioning mechanism comprising a pair of cylinders fixed in opposition to each other near the ends of the 70 frame, a pair of pistons mounted for reciprocatory rectilinear movement between and in alinement with the cylinders, a cross head rigidly connecting the pistons, said cross head having a transverse aperture with concentrically curved walls, a shoe having a central slot and concentrically curved outer sides fitting within the aperture, and a stem affixed to the bed and extending laterally therefrom into the slot of the shoe within 75 the aperture, substantially as described. 80

11. In a printing press, the combination, with a frame, and reciprocatory bed traveling longitudinally thereon in a curvilinear path, of a dash pot cushioning mechanism 85 comprising a pair of cylinders fixed in opposition to each other near the ends of the frame, a pair of pistons, mounted between the opposed cylinders, a cross head rigidly connecting the pistons and having arms extending laterally therefrom and guided within rectilinear grooves formed in the frame parallel to the axes of the cylinders, said cross head having a transverse aperture with concentrically curved walls, a shoe having a central slot and concentrically curved 90 outer sides fitting within the aperture, and a stem rigidly affixed to the bed and extending laterally therefrom into the slot of the shoe within 95 the aperture, substantially as described. 100
